(57) **CLAIM**

The ornamental design for a hook part, as shown and described.

DESCRIPTION

FIG. 1 is a perspective view of a hook part showing my new design;

FIG. 2 is a top view of the hook part shown in FIG. 1;

FIG. 3 is a front view of the hook part shown in FIG. 1;

FIG. 4 is a right side elevation view of the hook part shown in FIG. 1;

FIG. 5 rear view of the hook part shown in FIG. 1;

FIG. 6 is a left side elevation view of the hook part shown in FIG. 1;

FIG. 7 is a bottom view of the hook part shown in FIG. 1.

FIG. 8 is a perspective view of the hook part shown in FIG. 1, the broken lines of an over-door hook are for illustrative purposes only and form no part of the claimed design; and, FIG. 9 is a perspective view of the hook part shown in FIG. 1, the broken lines of mounting brackets are for illustrative purposes only and from no part of the claimed design.
